PLASTIC JUG

Norman A. Kelly, Wayne, Ind., assignor, by mesne assignments, to Haskon, Incorporated, Warsaw, Ind., a corporation of Delaware

Filed Mar. 7, 1966, Ser. No. 1,311

Term of patent 14 years

(Cl. D58—5)

FIGURE 1 is a perspective view of a plastic jug embodying my new design wherein the finish thereof is of the slip type as shown;

FIGURE 2 is a front elevational view;

FIGURE 3 is a side elevational view;

FIGURE 4 is a top plan view;

FIGURE 5 is a rear elevational view;

FIGURE 6 is a bottom plan view; and

FIGURE 7 is a side elevational view of a plastic jug showing another embodiment of my design, wherein the finish thereof is of the screw type as shown.

I claim:

The ornamental design for a plastic jug, as shown and described.
